G. Kline Tallett

Attorney

UNITED STATES PATENT OFFICE.

JAMES WILLIAM TRACY, OF SMITHLAND, KENTUCKY.

WRENCH.

1,388,131.

Specification of Letters Patent. Patented Aug. 16, 1921.

Application filed July 21, 1919. Serial No. 312,356.

To all whom it may concern:

Be it known that I, JAMES WILLIAM TRACY, a citizen of the United States of America, residing at Smithland, in the county of Livingston and State of Kentucky, have invented new and useful Improvements in Wrenches, of which the following is a specification.

The object of the invention is to provide a device which will possess in combination the features of an adjustable monkey wrench and an adjustable pipe wrench, a pair of pliers and wire cutters.

A further object of the invention is to provide a device of this kind which is simple in construction, durable and effective in operation and inexpensive to manufacture.

Other and further objects appear in the following description wherein the invention is set forth in detail.

To the exact construction in which it is shown and described, the invention is not to be restricted. The right is reserved to make such changes or alterations as the actual reduction to practice may suggest, in so far as such changes or alterations are compatible in spirit with the annexed claim.

The same numerals of reference designate the same parts throughout the drawing, wherein:

Figure 1 is a view partly in section and partly in elevation of the improved wrench.

Fig. 2 is a side elevational view, the handles being omitted.

Fig. 3 is an edge elevational view of the structure in Fig. 2.

Fig. 4 is a detail perspective view of one of the elements comprised in the active or movable jaw of the device.

As shown, the invention embodies what might be termed a passive jaw 1 and an active jaw 2. The jaw 1 is carried at the upper end of a bar 3 which is preferably rectangular in cross section and which is preferably formed integral with the jaw, this bar 3 also being formed integral with a disk element 4 which connects with the bar at the end remote from the jaw 1 and which has connected to it the handle 5, the latter connecting with the disk element at a point diametrically opposite the point of connection with the bar therewith.

A second handle 6 is embodied in the structure of the tool and this handle 6 is formed integral with a disk portion 7 of

similar shape to the disk portion 4 and the two handles are pivotally connected together by means of a pin or rivet 8 which passes centrally through them, thus holding them securely together. On diametrically opposite points on their edges, the two disks 4 and 7 are formed with the recesses 9 which register in certain positions of the handle and are thrown out of registration in other positions of the handle. Obviously a piece of wire placed in either of the notches when the two recesses of the two disks are in registration will be severed when the notches are thrown out of registration on the movement of the handles 5 and 6 toward each other.

The disk 7 at a point diametrically opposite the point of connection with the handle 6 is provided with an arm 10 in the upper edge of which is formed a slot 11, of the shape indicated in Fig. 1 of the drawing. In this slot there is pocketed one end of a link 12 which rocks on a pivot pin 13 passed transversely through the arm and across the slot and pivotally engaging the link. The other end of the link enters a similarly shaped slot 14 formed in a sliding bar 15, the latter having a rectangular eye formed therethrough through which the bar 3 passes. The block 15 may thus slide longitudinally along the bar 3 and such a movement will be imparted to the block on the rocking of the arm 10 such as will be imparted to the latter on the movement of the handles 5 and 6 toward and away from each other.

The block 15 is connected to the link 12 by means of a pin 16 which is passed transversely through the bar, across the slot and pivotally engaging the link as does the pin 13.

On that face of the bar 15 opposite the arm 10 there is formed a circular stud 17 this stud paralleling the bar 3 and being formed on that side opposite the bar 3 with a plurality of spaced teeth 18 in which the threads of a worm 19 may engage, this worm being pivotally mounted at one end by having its stud 20 engage a suitable bearing formed in the active jaw, the other end of the worm being supported on the end of a screw stud 21 which is threadingly engaged in the active jaw and enters the worm in axial alinement with the stud 20.

The active jaw 2 is slidably mounted on the bar 3 being formed with a rectangular eye similar to that formed in the bar 15. Thus the turning of the work 20, because of

its engagement with the teeth of the stud 17, will effect the adjustment of the active jaw 2 with reference to the bar 15. Therefore, when the handles are at rest with respect to each other, the active jaw may be adjusted with reference to the passive jaw.

With the handles 5 and 6 in closed position—that is, in a position when the upper edge of the arm 10 engages the under face 10 of the bar 15, as shown in Fig. 2 of the drawings, the active jaw is adjusted to suit the nut or pipe to be engaged by the device. When it is desired to release the jaw from engagement with the nut to change the position 15 of the device, the openings of the handles will effect this, the bar 15, as a result of this movement of the handle, sliding down the bar 3 and carrying with it the active jaw 2, thus separating the space between it and the passive jaw and permitting the 20 two to be readily disengaged from the nut or pipe for the purpose of effecting a new grip.

The facing surfaces of both the active 25 and the passive jaws are slotted transversely, the slots in the jaw 1 being relatively wide slots and being spaced relatively wide distances off to provide parallel ribs 22, the slots adjacent the outer ends of the 30 jaws being narrow slots and positioned close

together to provide the radial biting teeth 23 which are wedge shaped in cross section. Certain characters of pipe may necessitate the two jaws engaging the pipe, by means of the teeth 23, while other characters of pipe 35 on which the wrench is to be used may be better engaged by the teeth 22. Neither the teeth 22 nor the teeth 23 will prevent the effective operation of the two jaws on a nut.

The invention having been described, what 40 is claimed as new and useful is:

A tool of the kind described comprising a passive jaw formed with a bar, an active jaw 45 slidably mounted on said bar and movable toward and away from the passive jaw, a pair of pivotally connected handles one of 50 which is integrally connected with the bar and the other of which is formed with an arm in whose upper edge is formed a slot, a block slidably mounted on the bar and having a stud entering and loosely engaging the active jaw and formed with spaced teeth on one side, a link seated in the slot in the arm and pivotally connected with the block and 55 a worm rotatably mounted on the active jaw and engaged with the teeth in the stud.

In testimony whereof I affix my signature.

JAMES WILLIAM TRACY.
